UNITED STATES PATENT OFFICE.

WILLIAM M. SMITH, OF MERIDEN, CONNECTICUT, ASSIGNOR TO THE MERIDEN BRITANNIA COMPANY, OF SAME PLACE.

DESIGN FOR A COFFIN-HANDLE SOCKET.

SPECIFICATION forming part of Design No. 14,422, dated November 13, 1883.

Application filed August 20, 1883. Term of patent 14 years.

To all whom it may concern:

Be it known that I, WILLIAM M. SMITH, of Meriden, in the county of New Haven and State of Connecticut, have invented a new Design for a Coffin-Handle Socket; and I do hereby declare the following, when taken in connection with accompanying drawing and the letters of reference marked thereon, to be a full, clear, and exact description of the same, and which said drawing constitutes part of this specification, and represents a face view.

This invention relates to a design for a coffin-handle socket; and it consists in the configuration and ornamentation, as shown in the accompanying illustration.

The general outline of the socket is that of a parallelogram. At each angle a fan-shaped ornament springs from the body outward, and on each of the four sides is a straight bar representing a rope or cord having the appearance of running around the body of the socket

beneath the fan-shaped ornaments at the angles, those fan-shaped ornaments appearing to cover the bends in the rope. It is this corded margin of the socket, having the angles covered by the fan-shaped ornaments extending from the body of the socket, that constitutes the characteristic feature of this design.

I claim—

The design for coffin-handle socket, consisting of the body having a fan-shaped ornament extending therefrom at each angle, with the representation of a cord passing around the edge of the socket beneath said fan-shaped ornaments, as described, and shown in the accompanying illustration.

WILLIAM M. SMITH.
